UNITED STATES PATENT OFFICE.

WILLIAM H. STEWART, OF WORCESTER, MASSACHUSETTS.

FURNACE-DOOR FRAME.

1,333,225.

Specification of Letters Patent.

Patented Mar. 9, 1920.

Application filed June 5, 1919. Serial No. 301,876.

To all whom it may concern:

Be it known that I, WILLIAM H. STEWART, a citizen of the United States, residing at Worcester, in the county of Worcester and State of Massachusetts, have invented a new and useful Furnace-Door Frame, of which the following is a specification.

This invention relates to the frame for the door of a furnace and, while capable of general use, it is especially adapted for application to those types of heating furnaces which have front walls made of steel plates and are provided with cast iron door frames. Steel expands and contracts by heat and cold and cast iron expands to a different degree. This introduces inequalities which I find can be remedied in part by cooling the adjacent surfaces of the cast iron and steel. This I find can be accomplished, conveniently by introducing air to support combustion in a new way between these surfaces so as to keep them always in a comparatively cool condition.

The cast iron frames are of course somewhat irregular on their surfaces which come into contact with the steel plates and this invention has for another object to reduce these irregularities and consequently the difficulties which they present. This I accomplish by arranging the cast iron frame in such a way that it will bear on the steel front of the furnace over a much smaller area than heretofore, and I also provide an improved arrangement for the fastening means by which the frame will be held more effectively.

Further objects and advantages of the invention will appear hereinafter.

Reference is to be had to the accompanying drawings, in which—

Figure 1 is a front view of a part of a furnace showing the door frame with a preferred embodiment of this invention applied to it;

Fig. 2 is a sectional view of the same on the line 2—2 of Fig. 1 on enlarged scale;

Fig. 3 is a sectional view looking in from the rear on the line 3—3 of Fig. 2;

Fig. 4 is a sectional view on the line 4—4 of Fig. 1; and

Fig. 5 is a fragmentary plan looking in the direction of the arrow 5 in Fig. 4.

Although this invention is not limited to application to steel front furnaces I have shown it as applied to a furnace having a front made up of steel plates 10. These as

usual have an opening for the door. Surrounding this opening is a cast iron frame 11 which, instead of having a flange which fits against the front surfaces of the plates 10, is provided with a flange 12 spaced from this surface. This provides an air space 13 surrounding the door opening. This space is bounded on the outside by an inwardly extending rib 14 provided with a number of notches 15 in its edge. These notches are provided to permit the entrance of air into the space 13 and the rib 14 is provided to bear on the front surfaces of the plates 10.

On the inner side the frame 11 is provided with a flange 16 having a plurality of notches 17 equally spaced around it, none being provided on the bottom, which is continuous so as to prevent the entrance of ashes into the air space underneath. The notches 15 and 17 are spaced at convenient distances apart and are not usually in registration with each other, so that the air passing through will have to take a more or less sinuous course.

Another feature consists in the fact that the bolts 18 which fasten the frame to the front plates pass through the space 13 so that if there is a little spring to the cast metal they will hold the edge of the rib 14 firmly in contact with the front plates 10 and apply the pressure all around the periphery of the frame so as to secure a firm joint at this point.

In order to avoid any undue bending either of the flange 12 or the inner edge of the plates 10 these bolts are preferably guarded on each side by lugs 19 preferably cast integrally with the frame. These lugs do not extend quite to the surfaces of the plates 10 normally, but in case of any yielding they will serve as abutments to prevent its being excessive and will hold the plates 10 and flange 12 apart.

It is to be noted that the flange 16 extends in beyond the edge of the flange 14, so that its inner edge will be substantially flush with the inner surface of the boiler front 10. The door 20 is fastened to this frame 11 by the usual hinges 21 which need not be described in detail.

It will be seen that the frame is easily cast and that on account of the specific construction illustrated it is considerably lighter in weight than has been the case heretofore. This affords convenience in handling and a saving of metal. It is also

more firmly united to the boiler front on account of the construction described above and illustrated especially in Fig. 4, and affords a circulation of air through the notches 5 15 into the space 13 and through the notches 17 into the fire box. This will afford the air necessary to support combustion in the conjunction with the usual shutter 22. The notches 17 also tend to prevent cracking 10 due to expansion and contraction as they yield and take up the variation.

The air passing through the course above indicated keeps the adjacent surfaces of the boiler front 10 and the frame 11 cool so as 15 to reduce the amount of expansion and contraction and permit of the fitting of the cast iron frame more accurately to the boiler front opening than has been the case heretofore.

20 I am aware of the fact that the invention is applicable to furnaces having cast iron fronts as well as steel ones, but it has some additional advantages as stated above when used in the latter class of furnaces.

25 Although I have illustrated and described a specific embodiment of the invention I am aware of the fact that modifications can be made therein by any person skilled in the art without departing from the scope of the 30 invention as expressed in the claims. Therefore I do not wish to be limited to all the details of construction herein shown and described, but what I do claim is:—

1. An annular frame for a furnace door 35 having a flat flange spaced from the front of the furnace and provided with an inte-

gral marginal rib surrounding it and spaced from the edge of the door opening, said rib having a series of notches in its edge and the frame having an integral inner wall extending from the outer surface of the frame inwardly all around past said flange and then straight in from the flange to a plane just inside the door opening and having notches in its undermost edge. 40 45

2. In a furnace, the combination with a steel furnace front having a door opening, of a cast iron door frame, having a peripheral flange engaging the front surface of the steel front at a distance from the edge of 50 the door opening, constituting the only line of contact between front and frame, and having pairs of integral cast lugs located on the inside surface of said flange in position to almost touch the steel front, and fastening devices extending through the front and frame between said lugs to hold the edge of the flange firmly against the furnace front. 55

3. In a furnace, the combination with a furnace front having a door opening, of a door frame having a flange engaging the front surface of the front at a distance from the edge of the door opening, and having pairs of lugs located adjacent to each other 60 65 on the inside of said flange in position to almost touch the steel front, and a fastening device extending through the front and frame between lugs of each pair.

In testimony whereof I have hereunto 70 affixed my signature.

WILLIAM H. STEWART.
